Primary Examiner — Christy Nemeth(57) **CLAIM**

The ornamental design for a charging socket, as shown and described.

DESCRIPTION

FIG. 1 is a perspective view of a charging socket showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and

FIG. 8 is a bottom plan view thereof.

FIG. 9 is an enlarged partial view of area ‘9’ in FIG. 1.

FIG. 10 is an enlarged partial view of area ‘10’ in FIG. 2; and,

FIG. 11 is an enlarged partial view of area ‘11’ in FIG. 2. The dash-dot broken lines in the drawings illustrate portions of the charging socket that form no part of the claimed design. The dash-dot-dot broken lines illustrate the boundaries of the portions shown enlarged and form no part of the claimed design.

1 Claim, 11 Drawing Sheets(56)
